ELECTRIC PLUG

Samuel Thomas Ezzo, Port Henry, N. Y.

Application July 12, 1935, Serial No. 31,086

2 Claims. (Cl. 173—361)

This invention relates to an electric plug, the general object of the invention being to provide a plug in which there is no danger of the conductors within the plug being short circuited and 5 to so form the prongs that they will have a firm engagement with the openings of the female plug so that there is no danger of the plugs becoming separated until manually pulled apart.

This invention also consists in certain other 10 features of construction and in the combination and arrangement of several parts, to be herein-after fully described, illustrated in the accompanying drawings and specifically pointed out in the appended claims.

15 In describing the invention in detail, reference will be had to the accompanying drawings wherein like characters denote like or corresponding parts throughout the several views, and in which:—

20 Figure 1 is an elevation of the improved plug.

Figure 2 is an end view looking toward the small end of the prong carrying section.

Figure 3 is a section on the line 3—3 of Figure 2 but showing the front section connected with 25 the prong carrying section.

Figure 4 is a side view of the prong carrying section.

Figure 5 is an end view looking toward the outer end of the front section.

30 Figure 6 is an end view looking toward the pronged end of the prong carrying section.

Figure 7 is a view looking toward the inner end of the front section.

Figure 8 is a view of one of the prongs.

35 In these drawings, the letter A indicates the prong carrying section and the letter B the front or other section, each section being preferably of the shape shown and both sections are formed of suitable nonconducting material. The section B is formed with an internally threaded flange 1 for receiving the exteriorly threaded reduced part 2 of the section A so that the two sections are 40 detachably connected together. The section B is formed with a circular longitudinal extending hole 45 3 which is of considerable diameter and extends from one end through the other end.

Section A is hollow with its large end closed as at 4 and a partition member 5 divides the space formed by the hollow section into two chambers. 50 This partition has one end connected to the closure 4 and its other end is enlarged to provide a part 6 of circular shape in cross section and of the same length as the hole 3 in the section B, the parts being so arranged that when the two 55 sections are connected together the part 6 will

fill the hole in the section B. A prong 7 passes and through each chamber of the section A through a hole formed in the part 4, the outer end of the prong being corrugated as shown at 8 with the corrugations of substantially V-shape. 5 The inner end of each prong is rounded as shown at 9 and has a transverse hole 10 therein and a threaded hole extending inwardly from the end and intersecting the hole 10, the end hole being adapted to receive a screw 11 which acts to hold 10 the stripped end of a conductor 12 in the hole 10. These conductors pass through holes 13 in the part 6. The part of each prong which passes through a chamber is straight as shown at 7' and the chambers are filled with suitable non-conducting material 18 which terminates short of 15 the flange 2 as shown in Figure 3.

After the prongs are put in place and the filling material has been put in place it will be seen that the parts 9 carrying the holes 10 and 20 the holes for the screws 11 are exposed in the space left by the filling material 18 stopping short of the flange 2 so that the conductors 12 after being pushed through the holes in the part 6 can be readily connected with the parts 9 of the 25 prongs and then the section B is slipped over the part 6 and threaded to the flange 2. Thus it will be seen that the conductors and the prongs are thoroughly insulated from each other so that 30 there is no danger of the parts within the plug being short-circuited and due to the corrugated outer portions of the prongs they will make firm contact with the walls of the openings in the female plug and thus there is no danger of the 35 two plugs becoming accidentally separated and it will take a considerable pull on one plug to separate it from the other plug.

It is thought from the foregoing description that the advantages and novel features of the 40 invention will be readily apparent.

It is to be understood that changes may be made in the construction and in the combination and arrangement of the several parts, provided that such changes fall within the scope of the 45 appended claims.

What is claimed is:—

1. A plug of the class described comprising a section of non-conducting material, prongs carried by said section and extending from one end 50 thereof, the other end of the section having a space therein into which the inner ends of said prongs extend, a solid partition forming part of the section and dividing said space into two parts, said partition also separating the inner ends of 55

the prongs, an enlargement of circular shape in cross section connected with the outer end of the partition, the inner end of the enlargement being flush with the adjacent end of the section, 5 and said enlargement having separated longitudinally extending bores therein, conductors passing through said bores into the spaces formed by the partition, means for detachably connecting the inner ends of the conductors to the inner 10 ends of the prongs, and a second section of non-conducting material having a longitudinally extending opening therein for receiving the enlargement, and a flange on the inner end of said second section threaded to the inner end of the 15 first section.

2. A plug of the class described comprising a hollow section of non-conducting material having one end closed and its other end open, a threaded flange formed on the open end, a solid 20 partition dividing the section into two chambers, said partition extending from the closed end to a point flush with the end of the flange, a prong passing through each chamber, with portions of the prong projecting from the closed end of the 25 section, filling material in each chamber and extending to a point at the junction of the flange

with the section, whereby a space is formed at the flanged end of the section, which is divided into two parts by the partition, the inner ends of the prongs extending into said two parts of said space, an enlargement formed on that end 5 of the partition which divides said space, said enlargement being of circular shape in cross section and of elongated form and having its inner end flush with the end of the flange, said enlargement being provided with a pair of longi- 10 tudinally extending bores, each of which opens out into the space, one at each side of the partition, conductors passing through said bores, means for detachably connecting the inner ends 15 of the conductors to the ends of the prongs located in the two parts of the space, a second section of non-conducting material having a longitudinally extending opening therein for receiving the enlargement and having a flange 20 extending from its inner end which is threaded to the flange of the first section, the inner end of the second section abutting the end of the flange of the first section when the two flanges are threaded together.

25

SAMUEL THOMAS EZZO.
